PULL OR THE LIKE

Nolan K. Rhoades, Beloit, Wis., assignor to National Lock Co., Rockford, Ill., a corporation of Delaware

Filed Dec. 2, 1966, Ser. No. 4,902

Term of patent 14 years

(Cl. D10—8)

FIG. 1.

FIG. 2.

FIG. 3

FIG. 4.

FIG. 5.

FIG. 2 is a top plan view thereof;

FIG. 3 is a rear elevational view thereof;

FIG. 4 is an end elevational view thereof; and

FIG. 5 is a cross sectional view thereof taken on the line 5—5 of FIG. 2.

I claim:

The ornamental design for a pull or the like, substantially as shown.
